UNITED STATES PATENT OFFICE.

HENRY G. LORENTZ, OF HARTFORD, CONNECTICUT.

ENGINE-VALVE.

1,176,153.

Specification of Letters Patent. Patented Mar. 21, 1916.

Application filed February 28, 1912. Serial No. 680,490

To all whom it may concern:

Be it known that I, HENRY G. LORENTZ, a citizen of the United States, and a resident of Hartford, in the county of Hartford and State of Connecticut, have invented a new and useful Improvement in Engine-Valves, of which the following is a specification.

My invention relates to mechanism for controlling the inlet and exhaust passages of an engine, and an object of the invention, among others, is to provide a simple and efficient mechanism for accomplishing this purpose.

One form of device embodying my invention and in the construction and operation of which the object above set out, as well as others, may be attained, is illustrated in the accompanying drawings, in which—

Figure 1 is a view in cross section through a cylinder on plane denoted by dotted line 1—1 of Fig. 2. Fig. 2 is a view in longitudinal section through a cylinder on plane denoted by dotted line 2—2 of Fig. 1. Fig. 3 is a view in elevation of one of the cylinders of an engine, the balance being broken off. Fig. 4 is a detail perspective view showing a slide valve.

The invention is especially applicable to an engine of the explosive type, and for this reason I have selected such for the purpose of illustrating and describing my invention herein, although it will be understood that the invention is not necessarily limited to an invention of this class.

In the accompanying drawings the numeral 5 denotes a cylinder, (of which there may be a plural number embodied in a single structure if desired), having the usual chamber 6 for a piston (not shown). A base 7 is formed at the bottom of the cylinder that may rest upon any suitable bed such as that forming the crank case of an engine of this type. Openings 8 are formed through this base for the reception of valve rods 9 extending to valve mechanism to be hereinafter described. The upper part of the cylinder is enlarged diametrically to constitute a water jacket and in which a water chamber 10 is formed, depressions 11 being made in the wall of the water jacket and in which the valve rods 9 are located.

An inlet chamber or passage 12 is formed in one side of the cylinder near an end and an exhaust chamber or passage 13 is formed in the opposite side of the cylinder. This end of the cylinder is counterbored as at

14, recesses opening out of the counterbored part on diametrically opposite sides and constituting recesses 15 separated from the inlet and exhaust chambers by webs 16 rising from the flows of the inlet or exhaust passages. A cylinder head 17 is secured against the end of the cylinder and has a hub 18 projecting into the end of the cylinder and resting upon a shoulder 19 at the bottom of the counterbore 14. This hub is slightly smaller in diameter than the counterbore providing circular slideways 20 for valves 21. These valves are curved preferably on the arcs of circles, the valves having ports 22 opening to the inlet and exhaust chambers 12 and 13 each on opposite sides of a bridge 28, said bridges closing the mouths of the recesses 15, thus forming a well and shutting off the recesses from the explosion chamber, said recesses being also shut off from the inlet and exhaust by the webs 16. Flanges 50 extend laterally from the webs on the arc of a circle of which the center of the cylinder is the center, said webs forming seats for said valves. Inlet and exhaust ports 23—24 are formed through the head into the chamber in the interior thereof, which constitutes an explosion chamber 25. Each of the valves has an ear 26 located in the well formed by the valve and web 16 and to which ear one of the valve rods is secured, it being noted that this construction secludes the valve connections entirely from the inlet and exhaust passages and from the explosion chamber, so that there is no chance for the products of combustion exerting any injurious effect upon the valves and their operating mechanism. The usual opening 27 for a spark plug is formed in the cylinder head, opening into the explosion chamber. Any usual and ordinary form of mechanism for actuating the valve rods may be employed, this not forming part of the invention illustration thereof has been omitted. It will also be understood that where the term inlet or exhaust is used in describing the construction of any mechanism, this term may apply equally to either the inlet or exhaust.

It will be understood that the mechanism herein shown and described may be altered and changed to a considerable extent and yet embody the invention, and I do not therefore limit the invention to a valve mechanism constructed in exact accordance herewith.

I claim—

1. A cylinder having an explosion chamber with a passage communicating therewith and a counterbored end, a web projecting from the floor of said passage and counterbored end and forming a well with an opening through the bottom thereof, a cap to close said counterbored end and the upper end of said well, said cap having an extension of a size to form a space between it and said web, a sliding valve mounted in said space and having an ear extending into said well, and an operating rod secured to said ear and extending through the opening in the bottom of the well.
2. A cylinder having an explosion chamber with a passage communicating therewith and a counterbored end, a web extend-

ing from the floor of said counterbored end and passage and forming a well having an opening through the bottom thereof, said web having laterally extending flanges arranged concentrically with the axis of the cylinder, a cap to close the opening into said cylinder and well, said cap having a projection of a size to form a space between it and the flanges of said web, a valve of circular form located in said space and having an ear extending into said well, and an operating rod secured to the valve and extending through the opening in the bottom of said well.

HENRY G. LORENTZ.
